Primary Examiner — Ryan Harvey(57) **CLAIM**

The ornamental design for an amusement apparatus, as shown and described.

DESCRIPTION

FIG. 1.1 is a front view of the amusement apparatus;

FIG. 1.2 is a right side view thereof;

FIG. 1.3 is a left side view thereof;

FIG. 1.4 is a rear view thereof;

FIG. 1.5 is a top plan view thereof;

FIG. 1.6 is a bottom plan view thereof.

The portions of the elements shown in broken lines in FIGS. 1.1, 1.2, 1.4 form no part of the claimed design.

1 Claim, 6 Drawing Sheets(56)
